UNITED STATES PATENT OFFICE.

WILLIAM H. DE BUSK, OF CHICAGO, ILLINOIS, ASSIGNOR TO THE P & M COMPANY, OF CHICAGO, ILLINOIS, A CORPORATION OF ILLINOIS.

RAIL ANCHOR.

Application filed June 23, 1924. Serial No. 721,862.

To all whom it may concern:

Be it known that I, WILLIAM H. DE BUSK, a citizen of the United States, residing at Chicago, in the county of Cook and State 5 of Illinois, have invented certain new and useful Improvements in Rail Anchors, of which the following is a specification.

My invention relates to rail anchors, and it has for its object the provision of a new 10 and improved form and arrangement of parts in a device of this type, by which a double shackle hold can be had upon the flange of a rail for holding it from movement longitudinally, the shackle hold upon 15 the top and bottom faces of the flange of the rail being effected preferably by parts located at the same end of the anchor as that at which the anchor has its bearing upon the cross tie. It is one of the objects 20 of my invention to provide a construction of this type in the form of a casting, so arranged that there are no under-cut parts, the arrangement thus being such that the castings can very readily be produced.

It is another object of my invention to 25 provide new and improved means for holding the anchor normally in its gripping position, such means preferably comprising a small spring which shall function for holding 30 the anchor in the position in which the anchor is held by the pressure when there is a tendency for the rail to move longitudinally with respect to the cross tie.

It is another object of my invention to 35 improve devices of this type in sundry details, hereinafter pointed out. The preferred means by which I have accomplished my objects are illustrated in the accompanying drawings, and are hereinafter specifically described. That which I believe to be 40 new and desire to cover by this application is set forth in the claims.

In the drawings,—

Fig. 1 is a top plan view of my improved 45 anchor applied to a rail, partly broken away, the normal position of the spring being indicated by dotted lines.

Fig. 2 is a cross section taken on line 2—2 of Fig. 1.

Fig. 3 is a longitudinal sectional view, 50 taken substantially on line 3—3 of Fig. 1.

Fig. 4 is a view of the anchor as seen from the left in Fig. 1, a portion of the cross tie being shown in cross section.

Fig. 5 is a top plan view of a modified

form of construction, with the holding spring omitted.

Fig. 6 is a longitudinal sectional view, taken substantially at line 6—6 of Fig. 5.

Fig. 7 is a top plan view of another modified form of construction, with the holding spring also omitted in this view; and

Fig. 8 is a longitudinal sectional view taken substantially on line 8—8 of Fig. 7.

Referring now particularly to Figs. 1 to 4, 65 in which corresponding parts are indicated by the same reference characters, 10 indicates a railroad rail supported by a cross tie 11. Across the bottom face of the rail extends the body 12 of my improved anchor, 70 having a head 13 formed on one end thereof, and a head 14 formed on the other end. Extending longitudinally of the body 12, from the inner face of the head 14 is a short arm 15 which is adapted to engage 75 the upper face of the flange of the rail at that side of the rail. As is best shown in Fig. 3, the body 12 and the arm 15 are offset with respect to each other longitudinally of the rail, so that there is not any portion of 80 the one which is undercut with respect to the other. As is best shown in Fig. 3, the bottom face of the arm 15 and the top face of the body 12 are diagonally disposed so as to provide comparatively sharp bearings for 85 contact with the rail 10.

At its opposite end, formed with the head 13, I have provided a longitudinally extending arm 16 provided at its end portion with a lug 17 adapted to engage the upper 90 face of the flange at that side of the rail. As is clearly shown in Fig. 1, the lug 17 for engaging the upper face of the flange at one side of the rail is considerably in advance of the sharp edge bearing of the arm 95 15 upon the upper face of the flange at the opposite side of the rail.

As is also best shown in Fig. 1, each of the heads 13 and 14 is provided upon its inner face with a comparatively sharp bearing for 100 contact with the side face of the flange at that side of the rail. Such bearings are indicated by the numerals 18 and 19. These bearings are also arranged in spaced relation with respect to the body 12 of the anchor. These bearings are preferably provided by giving the inner faces of the heads 13 and 14 a double camber construction, as 105 is clearly shown in said Fig. 1. The head 14 is provided with a plate 20 which serves 110

as the bearing for the anchor against the cross tie 11.

For applying the anchor of Fig. 1 to the rail, the device is brought into position below the rail with the body of the anchor swung in counter clockwise direction with respect to the position of the body in Fig. 1. In such position, the arm 15 is first hooked over the flange at one side of the rail, after which the head 13 is raised so as to permit the lug 17 to pass the edge of the flange at the left in Fig. 1. Preferably the arrangement and construction are such that it is necessary to apply a slight force for enabling the lug 17 to pass the edge of the flange. When the lug 17 has been brought into position level with the upper face of the flange at that side of the rail, the anchor as a whole is swung in clockwise direction in Fig. 1 into substantially the position shown in Fig. 1, the lug 17 being caused to travel up the face of the flange toward the web of the rail as this swinging motion of the anchor continues. The arrangement and portions of the anchor are designed to be such that when the bearings 18 and 19, by contact with the side faces of the flange, stop the swinging motion of the anchor, at the same time the bearing portions of the arm 15 and the lug 17 will have been brought into contact with the upper faces of the flanges at opposite sides of the rail. With the anchor in this position, and with the bearing plate 20 in contact with the cross tie 11, any tendency of the rail to move longitudinally in the direction indicated by the arrow in said Fig. 1, will tend to swing the anchor in clockwise direction in said figure, by reason of the fact that the anchor has a bearing upon the cross tie at only one end of the anchor. At the same time, there will be a tendency to twist the anchor in counter clockwise direction, as shown in Fig. 3. The bearings 18 and 19 are accordingly brought into very tight gripping engagement with the side faces of the flange of the rail, and the bearing portions of the body 12 and the arm 15 are brought into very tight engagement with the top and bottom faces of the flange at the right in Fig. 1.

As will be readily understood, the shackle hold upon the top and bottom faces of the flange of the rail is effected by the arm 15 in connection with the body 12 of the anchor independently of any substantial gripping action of the lug 17. The lug 17 may accordingly be made just strong enough to keep the head 13 from dropping out of operative position with respect to the flange of the rail, the anchor being designed to permit sufficient yielding of the arm 17 to insure that the twisting pressure of the anchor about a transverse axis shall be resisted chiefly by the arm 15 rather than by the lug 17. Inasmuch as the bearings of the body 12 and the

arm 15 may be spaced at any desired distance from each other longitudinally of the rail, it will be understood that a very strong shackle hold or toggle grip can be effected by these parts upon the flange of the rail. In the same way, it will be understood that the bearings 18 and 19 can be spaced at any desired position longitudinally of the rail with respect to each other so as to provide the maximum shackle hold effect of such bearings upon the side faces of the flange.

For holding the anchor normally in its operative position, I have provided a spring 21 which is held in position within a groove in the upper face of the body 12. This spring normally stands underneath the base of the rail, as indicated by the dotted line positions in Figs. 1 and 4. As will be readily understood, when the spring is forced toward the left in Fig. 1 and is forced upwardly in Fig. 4 so as to bring its free end into engagement with the edge of the flange, the spring will then exert a pressure upon the anchor tending to hold the anchor in the position toward which the anchor is moved by the pressure when the rail tends to move in the direction indicated by the arrow in Fig. 1.

In the modified forms of construction as illustrated in Figs. 5 to 8, corresponding parts of the anchor are indicated by the same reference characters as are set forth above. In Figs. 5 and 7, the spring 21 is omitted, the groove in the upper face of the body 12 being indicated by the numeral 22.

In Figs. 5 and 6, the body 12 normally stands in diagonal position with respect to the directly transverse line across the rail. This effect is, of course, attained by an appropriate positioning of the bearings 18 and 19 with respect to each other, such bearings being at such a distance from each other that they are brought into contact with the side faces of the flange of the rail before the body of the anchor, in its swinging for application to the rail, as above described in connection with the device of Fig. 1, is permitted to come into the directly transverse position. In order to effect this result to advantage, the arm for engagement with the upper face of the flange adjacent to the point where the body of the anchor has its bearing upon the cross tie 11 is advanced with respect to the body 12 longitudinally of the rail so as to bring such arm into position overlying the cross tie 11. This arm in Figs. 5 and 6 is indicated by the reference character 23. As will be readily understood, the bearings 18 and 19 operate in the same manner as has been described above in connection with the device of Fig. 1. Likewise the bearings of the body 12 and the arm 23 are so related to each other as to have a shackle hold upon the flange in the manner

above described in connection with the arm 15 of the device of Fig. 1.

In Figs. 7 and 8, the construction is the same as that shown in Figs. 5 and 6, except 5 that the arm providing the bearing upon the upper face of the flange adjacent to the point where the body 12 bears against the cross tie 11 is not caused to extend above the cross tie. In lieu thereof an arm 24 is 10 provided, partially overlying the body 12, the arm 24 and the body 12 being provided with bearings intermediate their side faces, as is best shown in Fig. 8, in lieu of having such bearings located directly at the faces 15 of the parts as shown in Figs. 3 and 6. This is, of course, done without affecting the operation of the device.

So far as I am aware, I am the first in the art to provide a rigid anchor of this type 20 in the form of a casting, adapted to be applied to a rail by a horizontal swinging motion with respect thereto, with the bearings of the device upon the rail so arranged with respect to each other that the anchor 25 is brought to its operating gripping position before the body of the anchor reaches the directly transverse position.

So far as I am aware, I am the first in the art to provide a device of this type with a 30 spring or other resilient means so arranged as to have a tendency to swing the anchor into its gripping position, the arrangement being such that the action of the spring is auxiliary to the pressure for causing a tightening of the anchor upon the rail when there 35 is a tendency for the rail to creep rather than counter to the pressure.

While I prefer to employ one of the constructions as illustrated in the drawings and 40 as above described, it will be understood that I do not desire to limit myself to the precise construction as illustrated, except as the same may be hereinafter specifically claimed, inasmuch as it is evident that various changes might be made in the construction without departing from the spirit of 45 my invention.

Having described my invention, what I 50 claim is:

1. A rail anchor comprising a rigid body adapted to extend across beneath a rail, rigid bearings on said body adapted to engage the side faces of the flange of the rail, other rigid bearings on said body adapted 55 to engage the top and bottom faces of the flange of the rail, and a bearing on said body adapted by engagement with the cross tie when there is a tendency for the rail to creep to swing the anchor slightly with respect to the rail for causing a tight operative shackle grip upon the side faces of the flange and also on the top and bottom faces of the flange at the side of the rail adjacent the tie engaging portion of the anchor.

2. A rail anchor comprising a rigid body

adapted to extend across beneath a rail, rigid bearings on said body adapted to engage the side faces of the flange of the rail, other rigid bearings on said body adapted to engage the top and bottom faces of the flange of the rail, a bearing on said body adapted by engagement with the cross tie when there is a tendency for the rail to creep to swing the anchor slightly with respect to the rail for causing a tight operative shackle grip upon the side faces of the flange and also on the top and bottom faces of the flange, and a spring tending to hold 70 said anchor in its operative gripping position. 75

3. A rail anchor comprising a rigid body adapted to extend across beneath a rail, rigid bearings on said body adapted to engage the side faces of the flange of the rail, other rigid bearings on said body adapted to engage the top and bottom faces of the flange of the rail, a bearing on said body adapted by engagement with the cross tie when there is a tendency for the rail to creep to swing the anchor slightly with respect to the rail for causing a tight operative shackle grip upon the side faces of the flange and also on the top and bottom faces of the flange, and a single spring 80 tending to swing the anchor about both horizontal and vertical axes for tightening the 85 said two shackle holds. 90

4. A rail anchor comprising a rigid body adapted to extend across beneath a rail, rigid bearings on said body adapted to engage the side faces of the flange of the rail, other rigid bearings on said body adapted to engage the top and bottom faces of the flange of the rail, a bearing on said body adapted by engagement with the cross tie 100 when there is a tendency for the rail to creep to swing the anchor slightly with respect to the rail for causing a tight operative shackle grip upon the side faces of the flange and also on the top and bottom faces of the flange, and a spring fitted in a groove 105 in the top face of the body of the anchor and held in position by contact with the rail tending to hold said anchor in its operative 110 gripping position. 115

5. A rail anchor comprising a rigid body adapted to extend across beneath a rail, rigid bearings on said body adapted to engage the side faces of the flange of the rail, other rigid bearings on said body adapted to engage the top and bottom faces of the flange of the rail, a bearing on said body adapted by engagement with the cross tie 120 when there is a tendency for the rail to creep to swing the anchor slightly with respect to the rail for causing a tight operative shackle grip upon the side faces of the flange and also on the top and bottom faces of the flange, and a spring operatively connected with the anchor at one end and 125 130

adapted to have its free end moved both laterally and vertically into engagement with the edge of the flange against the force of the spring, whereby it is enabled to 5 tighten the anchor yieldingly in gripping position.

6. A rail anchor comprising a bar, a head formed on each end of said bar, bearings on said heads adapted to engage the side 10 faces of the flange of the rail, an arm extending along the body from the inner face of one of said heads, bearings on said arm and said body adapted to engage the top and bottom faces of the flange, and a bearing 15 on said body adapted by engagement with the cross tie to tighten said bearings on said flange.

7. A rail anchor comprising a bar, a head formed on each end of said bar, bearings on 20 said heads adapted to engage the side faces of the flange of the rail, an arm extending along the body from the inner face of one of said heads in spaced position longitudinally of the rail with respect to the body, 25 bearings on said arm and said body adapted to engage the top and bottom faces of the flange, and a bearing on said body adapted by engagement with the cross tie to tighten said bearings on said flange.

30 8. A rail anchor comprising a bar, a head formed on each end of said bar, bearings on said heads adapted to engage the side faces of the flange of the rail, an arm extending along the body from the inner face 35 of one of said heads, bearings on said arm and said body adapted to engage the top and bottom faces of the flange, and a bearing on said body at the end adjacent to said arm adapted by engagement with the cross 40 tie to swing said anchor about both horizontal and vertical axes for causing said bearings to have a shackle hold upon the side faces of the flange and also upon the top and bottom faces of the flange.

45 9. A rail anchor comprising a rigid body adapted to extend across beneath a rail, bearings carried by the body at its ends in spaced position longitudinally of the rail with respect to the body and adapted to engage 50 the top face of the flange of the rail at opposite sides thereof, other bearings adapted to engage the side faces of the flange of the rail, the arrangement being such that the anchor may be applied to the 55 rail by a horizontal swinging motion for bringing both of said first named bearings into operative position on the upper face of the flange, and such that the contact of the second named bearings with the side faces 60 of the flange limits the swinging motion of the anchor horizontally with respect to the rail, and a bearing carried by the body at

one end thereof for contact with the cross tie.

10. A cast rail anchor comprising a rigid 65 body adapted to extend across beneath a rail, bearings formed integrally with the body at its ends adapted to engage the top face of the flange of the rail at opposite sides thereof, other bearings formed integrally with the body and adapted to engage the side faces of the flange of the rail, the arrangement being such that the anchor may be applied to a rail by a horizontal swinging motion for bringing both of said first named bearings into operative position 70 on the upper face of the flange, and such that the contact of the second named bearings with the side faces of the flange limits the swinging motion of the anchor horizontally with respect to the rail, the arrangement of the bearings being such also that they are brought into operative gripping position in the horizontal swinging motion 75 of the body before the body reaches the directly transverse position with respect to the rail.

11. A rail anchor comprising a bar, a head on each end of said bar, bearings on the inner faces of said heads adapted to engage the side faces of the flange of a rail, and projections from the inner faces of the heads and located in spaced relation with respect to the body of the anchor longitudinally of the rail on the same face of the body and adapted to be brought into engagement with the upper face of the flange 90 of the rail by a horizontal swinging motion of the anchor with respect to the rail.

12. A rail anchor comprising a bar, a head on each end of said bar, bearings on the inner faces of said heads adapted to engage the side faces of the flange of a rail, and projections from the inner faces of the heads adapted to be brought into engagement with the upper face of the flange of the rail by a horizontal swinging motion of the anchor with respect to the rail, one of 100 said projections being adapted to be swung into position overlying the cross tie.

13. A rail anchor comprising a bar, a head on each end of said bar, bearings on the inner faces of said heads adapted to engage the side faces of the flange of a rail, and projections from the inner faces of the heads adapted to be brought into engagement with the upper face of the flange of the rail by a horizontal swinging motion of the anchor with respect to the rail, both of 110 said projections being adapted in the applied position of the anchor to overlie the cross-tie.

WILLIAM H. DE BUSK.
